UNITED STATES PATENT OFFICE.

EDWARD G. BLOSER, OF LOS ANGELES, CALIFORNIA.

RUBBER HEEL.

Application filed May 7, 1923. Serial No. 637,271.

To all whom it may concern:

Be it known that I, EDWARD G. BLOSER, a citizen of the United States, residing at Los Angeles, in the county of Los Angeles and 5 State of California, have invented new and useful Improvements in Rubber Heels, of which the following is a specification.

My present invention is a rubber heel; and it is a primary object of this invention 10 to utilize the principle of the vacuum cup in preventing the slipping of a rubber heel.

It is a further object of this invention to provide a rubber heel with a cavity of substantial size, and such as may serve, by inter- 15 fitting with irregularities in the surface of the ground traversed, mechanically to prevent slipping.

It is a further object of this invention to so reduce the contact surface of a rubber heel with the ground traversed that the marginal portions about a central vacuum cup may be capable of forming a slight depression in ground traversed, thereby preventing 20 slippage.

It is a further object of this invention to provide a rubber heel of the character referred to which may be so formed on its upper surface as to facilitate a satisfactory fit upon the bottom of a shoe to which it is 25 to be attached.

Broadly, it is an object of this invention to provide a heel within which may be incorporated any desired reinforcement, which may be easily attached in a usual manner, 30 and which shall be especially suitable for use upon tennis shoes, or hiking shoes, or other shoes for the use of athletes, but which shall also be suitable for general use wherever a rubber heel is desired.

Other objects of my invention will appear from the following description of a preferred embodiment thereof, and the appended claim, taken in connection with the accompanying drawings, in which—

Fig. 1 is a side elevation of a shoe provided with a rubber heel of my preferred design, this heel being shown partly in section.

Fig. 2 is a transverse section of a heel of my preferred design, the introduction of reinforcement, as indicated by dotted lines, being optional.

Fig. 3 is a bottom view, and

Fig. 4 is a side view of the form of heel shown in Fig. 2.

In the form of my invention which I have chosen for illustration, it will be understood that 1 may be a suitably molded mass of rubber or equivalent material constituting the body of the heel, this heel being provided with a circular arched depression or vacuum cup 2 in the bottom thereof, and provided with a reinforcing element 3, which may be of canvas or other suitable material, and also with apertures 4, adapted to receive the nails by which the heel may be secured, provision for the countersinking of the heads 5 of the nails being made in the manner indicated at 6, and washers 7 for the better securing of the said nails 70 being inserted in advance of the vulcanization of the said heel.

I prefer to so form a heel of the character described that it shall snugly fit the bottom of a shoe to which it may be applied, 75 and for this purpose I may so mold the heel to form two flat lateral halves of the attaching face oppositely inclined to the longitudinal line 8, as best shown in Fig. 2.

By the foregoing construction it will be 80 obvious that, when a rubber heel of the character described is properly applied to the bottom of a shoe, and thereby suitably flattened, a cup formed of resilient material, and adapted to produce a suction relative to 85 any smooth surface, such as the surface of a concrete sidewalk, is provided. It is important that the vacuum cup 2 be circular in plan and arched in vertical cross-section, and the diameter of the cup should be substantially half the transverse width of the heel, in order to attain the objects indicated above. It being well known that rubber soles or heels are especially liable to slip upon a wet stone or concrete or metallic surface, it will be understood that, when the wearer of a shoe provided with a heel of my preferred design is traversing such a surface, the first effect of a contact between a heel of this design and a surface of the character referred to must be the pressing of air from within a cup; and this escape of air, producing a suction effect, tends to secure the heel to the pavement and thereby diminish the risk of a dangerous fall. Although the area of the suction cup 2 may vary within wide limits, I find it preferable to so form this cup that its area shall be not less than approximately one-fourth the area of the bottom of the heel.

Although I have described one preferred form of my invention, it will be understood that various modifications of the same are possible without a departure from the spirit and scope of this invention as the same is indicated above and in the following claim; and although I prefer to use the inclined upper faces forming a line 8 together with the vacuum cup 2, it will be understood 10 that the features of construction referred to are capable of either separate or conjoint use.

I find a substantially circular central vacuum cup to be more effective than an aperture having angles, and it should also be understood that, although in the use of my rubber heel I prefer to secure the same initially by nailing it approximately in the median line, as through the holes N, N', 20 thereby slightly flattening the heel and assuring a tight fit at its edges, my novel heel

may optionally be secured in any other usual or desired manner.

What I claim is:—

A rubber heel having two lateral halves 25 with parallel faces, oppositely inclined with the top surfaces meeting at a longitudinal center line at an angle, a U-shaped flexible fabric reinforcing member following the side and back contour of the heel, the reinforcing member being inserted parallel with the flat surfaces of the heel, washers imbedded in the heel adjacent the reinforcing member; securing means passing 30 through the washers and reinforcing member, and a single vacuum cup on the bottom face of the heel situated within the U-shaped reinforcing member.

In testimony whereof I have signed my name to this specification.

EDWARD G. BLOSER.
